UNITED STATES PATENT OFFICE.

MORRIS P. BRAY, OF NEW HAVEN, CONNECTICUT.

CORSET.

SPECIFICATION forming part of Letters Patent No. 280,565, dated July 3, 1883.

Application filed March 30, 1883. (No model.)

To all whom it may concern:

Be it known that I, MORRIS P. BRAY, of New Haven, in the county of New Haven and State of Connecticut, have invented a new Improvement in Corsets; and I do hereby declare the following, when taken in connection with accompanying drawings and the letters of reference marked thereon, to be a full, clear, and exact description of the same, and which said drawings constitute part of this specification, and represent, in—

Figure 1, a part of a section of a corset, showing the stays in place; Fig. 2, a transverse section of the stay enlarged; Fig. 3, a face view 15 of the stay.

This invention relates to an improvement in corsets, and stays to be used in the manufacture of corsets, the object being to produce a stay composed of parallel cords, but which 20 shall give to the corset substantially the appearance of bones; and the invention consists in the construction of the stay and of the corset, as hereinafter described, and more particularly recited in the claims.

I produce the stay by weaving a strip, A, Fig. 3, of suitable width for the stays of a section of a corset. In this strip, at intervals, pairs of cords *a b* are introduced, the two cords composing each pair set as close together as may be, leaving only two warp-threads, *c d*, between them. Between the 30 pairs of cords several warp-threads *e* are introduced, as in common weaving. The filling *g* is introduced and interwoven with the cords and the warps, the filling passing alternately over and under the cords, in the usual manner of weaving, and in the passage of the filling *g* it is interlaced with the intermediate warps, *e*. This leaves a flat space or web, *f*, between 35 the pairs of cords *a b*, as seen in Figs. 2 and 40 3. The cords lying so closely together appear

as a broad rib, *h*, projecting upon both surfaces, as seen enlarged in Fig. 2.

The cord used should be hard and of a nature to give a certain amount of stiffening to 45 the strip. The strip thus produced is cut into lengths required for the respective sections of the corset.

The stay is introduced between the outer and inner thicknesses, *i l*, of the corset, and lines of 50 stitches *m* run through the web portion *f*, between the pairs of cords, as seen in Figs. 1 and 2, giving to the surface a ribbed appearance, the same as the introduction of bones in pockets produces, and at a much less cost than 55 bones can be procured.

I illustrate in Fig. 1 only a portion of one section of corset; but that will be sufficient to enable those skilled in the art to apply this improved stay to other sections. 60

I claim—

1. The herein-described stay, consisting of a strip composed of pairs of cords *a b*, with series of warp-threads *e* between said pairs, the said cords and warp-threads interlaced 65 with the filling-thread *g*, whereby webs *f* are formed between said pairs of cords, substantially as described.

2. A corset composed of two thicknesses of fabric, combined with stays introduced between said thicknesses, composed of pairs of cords, *a b*, with warp-threads *e* between the cords, interlaced by filling-threads *g* to form webs *f* between said pairs of cords, said warp-threads and cords being united by the filling 70 in the process of weaving, and the said thicknesses of the corset stitched together through the said webs, substantially as described. 75

MORRIS P. BRAY.
